DESIGN FOR A UKULELE OR SIMILAR STRING INSTRUMENT

John Ying Git Lai, Honolulu, Territory of Hawaii

Application July 17, 1939, Serial No. 86,053

Term of patent 14 years

To all whom it may concern:

Be it known that I, John Ying Git Lai, a citizen of the United States, residing at Honolulu, Territory of Hawaii, have invented a new, original, and ornamental Design for a Ukulele or Similar String Instrument, of which the following is a specification, reference being had to the accompanying drawing, forming a part thereof.

Figure 1 is a front elevation of a ukulele or similar string instrument, embodying my new design; and

I claim:

The ornamental design for a ukulele or similar string instrument, as shown.

JOHN YING GIT LAI.
